A. NESBITT.
ADJUSTER FOR ELECTRIC LIGHT CABLES.
APPLICATION FILED OCT. 6, 1917.

Patented Apr. 23, 1918.

INVENTOR
Alexander Nesbitt.
BY Charles R. Searle.

ATTORNEY

UNITED STATES PATENT OFFICE.

ALEXANDER NESBITT, OF PATERSON, NEW JERSEY.

ADJUSTER FOR ELECTRIC-LIGHT CABLES.

1,263,795.

Specification of Letters Patent. Patented Apr. 23, 1918.

Application filed October 6, 1917. Serial No. 195,174.

To all whom it may concern:

Be it known that I, ALEXANDER NESBITT, a citizen of the United States, residing at Paterson, in the county of Passaic and State 5 of New Jersey, have invented a certain new and useful Improvement in Adjusters for Electric-Light Cables, of which the following is a specification.

The invention relates to means for lengthening or shortening the loop in the suspension cable of an electric lamp and thus raising or lowering the latter, and the object of 10 the invention is to provide simple, easily operated means by which the desired variations in the elevation of the lamp may be effected without abrasive action on the cable tending to fray the covering and damage the insulation, and a further object is to provide 15 means for automatically holding the cable in the adjusted position.

The invention consists in certain novel features and details of construction and arrangement by which the above objects are attained, to be hereinafter described and 20 claimed.

The accompanying drawings form a part of this specification and show two forms of the invention.

Figure 1 is an elevation showing the device supporting an electric lamp cable, and its relation to the latter and the lamp.

The remaining figures are on a larger scale.

Fig. 2 is a side elevation of the device attached to the cable, corresponding to Fig. 1.

Fig. 3 is a plan or top view.

Fig. 4 is a vertical section, taken on the line 4—4 in Fig. 3, and partly in elevation.

Fig. 5 is a side elevation of a modified 40 form adapted to be fastened directly upon the ceiling or other suitable support.

Similar letters of reference indicate like parts in all the figures.

Referring to Figs. 1 to 4 inclusive, A indicates an incandescent electric lamp bulb attached as usual to a cable A¹ suspended from the ceiling or other support.

B is a casing, shown as a block of fiber, wood, or other nonconducting material, having 50 a vertical tapered dovetailed channel b on one face, the wall of which is provided with a vertical groove b¹ receiving and partially encircling the cable A¹, and C is a tapered dovetailed wedge matching to the

channel and forced therein from below. It 55 has a vertical groove c corresponding to the groove b¹ and completing the inclosure of the cable. By slackening the wedge C the cable is released and the block B moved up or down to a new position on the cable, and 60 when again tightened grasps the cable reliably at the selected height thereon but without danger of damage thereto.

The block B is hollowed or provided with a pocket b² in its upper face, in the lower 65 portion of which is a grooved sheave D mounted to revolve on a stud D¹ extending through the block, and E² is a lever mounted on a stud E¹ and carrying at its inner end a wheel E having a circumferential ridge e 70 adapted to lie in the groove of the sheave.

The outer end of the lever E² extends beyond the block B and is held normally upward by a helical expansion spring F received in a vertical recess b³ in the block 75 and exerting its force to lift the outer end of the lever and hold the wheel E in frictional contact with the sheave D.

G is a cord attached at one end to the overhung end of the lever E², extending 80 thence downwardly in a bight or loop and again upwardly and is passed through a vertical hole b⁴ in the block, partially around and over the sheave D and thence downwardly through a second guide-hole b⁵ 85 in the block, and its end secured to the cable A¹ at a point considerably below the block, as shown in Fig. 1. The cord thus forms three vertical members g, g¹ and g².

A continued downward pull on the member 90 g tilts the lever E² and lifts the wheel E out of contact with the cord in the groove of the sheave D and permits the lamp A to be raised or lowered through the shortening or lengthening of the member g² by manipulating the member g¹ aided by the gravity of the lamp and cable. On releasing the member g the spring F forces the ridge of the wheel E into strong frictional contact with the cord in the groove of the sheave D and 100 holds the lamp in the adjusted position. The lever E² with its wheel E thus serves as a brake for the cord and its sheave.

The form of the invention shown in Fig. 5 is designed to be attached to the ceiling 105 or other support instead of directly upon the cable. In this form the casing B¹ being out of contact with the cable, may be of

sheet metal having lugs B² receiving screws H for securing it in place. It is equipped with a grooved sheave D², lever E⁴, wheel E³ and spring F¹, all operated as before 5 through the cord G¹.

I claim:—

1. In a device of the character set forth, a casing, a sheave therein, a cord traversing said casing and partially around said sheave, and adapted to be attached to a lamp-cable below said casing, a lever mounted in said casing, a wheel carried by said lever and adapted to engage said cord in its passage over said sheave, a spring arranged to force 10 said lever and wheel into such engagement, and means for tilting said lever in opposition to said spring.
2. In a device of the character set forth, a casing, clamping means for adjustably attaching said casing to a lamp-cable, a cord traversing said casing and adapted to be attached to and support said lamp-cable below said casing, a brake mounted in said casing and arranged to act frictionally on 15 said cord in such traverse, and means for operating said brake.
3. In a device of the character set forth, a casing, clamping means for adjustably attaching said casing to a lamp-cable, a sheave 20 in said casing, a cord traversing said casing and partially around said sheave, and adapted to be attached to said lamp-cable below said casing, a brake mounted in said casing and arranged to act frictionally against said 25

cord and sheave, and means for operating 35 said brake.

4. In a device of the character set forth, a casing, clamping means carried by said casing for attaching the latter adjustably upon a lamp-cable, a cord traversing said 40 casing and adapted to be attached to said cable below said casing, a spring-actuated brake mounted in said casing and arranged to act frictionally on said cord in such traverse, and means for operating said 45 brake.

5. In a device of the character set forth, a casing having a vertical tapered dovetailed channel therein and a vertical groove in such channel, a dovetailed wedge matching 50 in said channel and having a vertical groove therein, serving with said casing to grasp a lamp-cable received in such grooves, a sheave mounted in said casing, a cord traversing said casing and partially around 55 said sheave and adapted to be attached to said cable below said casing, a lever mounted in said casing, a wheel carried by said lever and adapted to engage said cord in its passage over said sheave, a spring in said casing 60 arranged to force said lever and wheel into such engagement, and a cord attached to said lever for tilting the latter in opposition to said spring.

In testimony that I claim the invention 65 above set forth I affix my signature.

ALEXANDER NESBITT.
